CLAIM

The ornamental design for a controller with removable paddles, as shown and described.

DESCRIPTION

FIG. 1 is a rear perspective view of a controller with removable paddles showing our new design in a first, attached state;

FIG. 2 is a bottom view thereof;

FIG. 3 is a rear view thereof;

FIG. 4 is a front view thereof;

FIG. 5 is a left side view thereof;

FIG. 6 is a right side view thereof;

FIG. 7 is a top view thereof;

FIG. 8 is a rear perspective view of the controller with removable paddles of FIGS. 1-7 shown in a second, removed state;

FIG. 9 is a bottom view thereof;

FIG. 10 is a rear view thereof;

FIG. 11 is a front view thereof;

FIG. 12 is a left side view thereof;

FIG. 13 is a right side view thereof; and,

FIG. 14 is a top view thereof.

The broken line showing of the various unshaded elements of the controller with removeable paddles in FIGS. 1-14 is for environmental purposes only and forms no part of the claimed design.
